UNITED STATES PATENT OFFICE

WALTER T. WINCKLER, OF CHICAGO, ILLINOIS, ASSIGNOR TO VON WINKLER LABORATORIES, INCORPORATED, A CORPORATION OF ILLINOIS

PHARMACEUTICAL COMPOUND AND PROCESS FOR MAKING SAME

No Drawing. Application filed November 7, 1928. Serial No. 317,884.

This invention relates to an improved pharmaceutical compound for the treatment of germ diseases and particularly to a specific for gonorrhea.

- 5 The main objects of this invention are to provide an improved method for making a pharmaceutical compound for employing chemically combined silver in a form which will resist decomposition, to provide an organic compound containing silver for the curing of acute and advanced states of gonorrhea and healing tissue infected therewith, to provide a pharmaceutical compound of the class described for preventing the conception 10 of gonorrhea, to provide a soluble composition that will effectively attack disease germs, especially gonococcus, and without causing irritation or burning.

Heretofore silver has been used in various 20 chemical combinations, such as for example, silver albuminates, for the treatment of infections and germ diseases, but great difficulty has been encountered in obtaining soluble compounds of silver which are stable, non-irritative when applied to animal membrane, and effective as gonococcus destroying 25 agents.

I have found that when vegetable oils containing fatty acids are sulphonated they provide organic chemical structures in which silver or other rare metals may be conveniently combined in such a manner as to produce a compound that is stable, non-irritative, and effective as a germ-destroying agent. The 30 silver, or other rare metal, is preferably introduced into the sulphonated vegetable oil in the form of an organic ammonium structure.

Numerous different oils, both vegetable 40 and animal, containing fatty acids of many different varieties may be used in the preparation of my improved pharmaceutical compound, and these may be combined with various rare metal compounds, but for the purpose of illustrating a specific example of my method of producing an improved compound of the class described, the following ingredients are employed.

Four parts of castor oil are treated with 45 one part of sulphuric acid, by weight, in any

suitable receptacle. The ricinol acid of the castor oil is sulphonated to sulphoricin acid during this reaction, and the product obtained thereby is neutralized after the reaction is completed with sodium hydroxide. 55 Sufficient sodium hydroxide, preferably in solution form, is added to produce a product neutral to phenolphthalein. The sodium sulphate formed during the neutralizing step is precipitated by dissolving the neutralized sulphoricin acid in a quantity of suitable solvent, preferably alcohol substantially equal in weight to the castor oil originally used. The sodium sulphate precipitate is later removed by filtration, leaving substantially chemically pure sulpho-ricin acid in solution. 60 65

Silver is then introduced into the compound by the addition of silver ammonium formate to the sulpho-ricin acid, producing 70 sulpho-ricin silver ammonium formate.

The quantity of silver ammonium formate required for the treatment of 100 cubic centimeters of sulpho-ricin acid may be made by dissolving one grain of silver nitrate in three and one-half cubic centimeters of ammonium hydroxide and adding formic acid thereto. Sufficient formic acid is added to the silver solution, by the method of titration, to render 75 it only slightly alkaline, the proper end point being indicated by the occurrence of a slight change in color. The precipitation of silver formate is avoided by the presence of the ammonium hydroxide and the slight alkalinity of the solution remaining after the addition of the formic acid. The resulting sulpho-ricin silver ammonium formate when compounded in the manner illustrated, contains 80 85 substantially 1% silver, by weight.

The final sulpho-ricin silver compound has the characteristics of stability, solubility, is non-irritating and highly effective for destroying gonococcus. Since the absolute composition of castor oil is not known, it is impossible to write a formula for the compound. 90 95

Although but one specific example of my invention has been herein described, it will be understood that various changes in the details and sequence of steps of the process and substitutions of ingredients may be made 100

without departing from the spirit of this invention as defined by the following claims:

I claim:

- 5 1. The method of preparing a pharmaceutical compound consisting of sulphonating a fatty acid, introducing silver into chemical combination with the sulphonated fatty acid by the addition of silver ammonium formate thereto.
- 10 2. The method of manufacturing a specific for gonorrhea consisting of sulphonating ricin acid, and treating the sulphonate ricin acid with silver ammonium formate.
- 15 3. The method of manufacturing a specific for gonorrhea consisting of treating castor oil with sulphuric acid to form sulpho-ricin acid, neutralizing the latter with an alkali, dissolving the neutralized sulpho-ricin acid in alcohol, and treating the alcohol solution with a solution containing silver to chemically combine the latter therewith.
- 20 4. The method of making a pharmaceutical compound consisting of treating four parts of castor oil with substantially one part, by weight, of sulphuric acid, neutralizing the reaction product with sodium hydroxide, dissolving the neutralized product in alcohol, combining silver with the alcohol solution by adding silver ammonium formate thereto.
- 25 5. A specific for gonorrhea comprising sulpho-ricin silver ammonium formate.

Signed at Chicago this 31st day of October, 1928.

WALTER T. WINCKLER.
